UNITED STATES PATENT OFFICE.

HENRY E. EBERHARDT AND FRED L. EBERHARDT, OF NEWARK, NEW JERSEY, ASSIGNORS TO GOULD & EBERHARDT, OF NEWARK, NEW JERSEY, A CORPORATION OF NEW JERSEY.

METAL-PLANING MACHINE.

No. 821,932.

Specification of Letters Patent.

Patented May 29, 1906.

Application filed June 3, 1903. Serial No. 159,846.

To all whom it may concern:

Be it known that we, HENRY E. EBERHARDT, residing at 113 Orchard street, and FRED L. EBERHARDT, residing at 17 Hillside 5 avenue, Newark, county of Essex, State of New Jersey, both citizens of the United States, have invented certain new and useful Improvements in Metal-Planing Machines, fully described and represented in the following 10 specification and the accompanying drawings, forming a part of the same.

The present improvements relate to that class of metal-planing machines, commonly called "shapers," in which the work-piece is held stationary and the tool is moved over the same by a reciprocating ram.

The invention consists partly in an improved construction for the vibrating feed-arm which intermittently operates the feed-screw in the cross-head of the machine, partly in a special arrangement of mechanism to drive the pitman crank-pin at two different rates of speed, and partly to a particular construction of the frame of the shaper and the combination therewith of an electric motor and clutch-gearing for rotating the crank-gear.

In the drawings, Figure 1 is a side elevation of a shaper provided with our improvements, the hand-wheel s^2 being omitted to expose the clutch. Fig. 2 is a cross-section on line 2 2 in Fig. 1, the base not being shown in section. Fig. 3 is a plan of the rear end of the machine with the guard over the gearing in section. Fig. 4 is a rear elevation. Fig. 5 is a vertical section on line 2 5 in Fig. 1. Fig. 6 is a side view of the oscillating feed-arm; Fig. 7, a section on line 7 7 in Fig. 6; Fig. 8, a front view of the feed-arm and the 40 gearing connections which oscillate the same. Fig. 9 is a section of the pinion-shifting appliances, and Fig. 10 is a side elevation of a portion of the frame which supports the pinion-shifting appliances.

The shaper is shown in the drawings with a box-frame having flat sides A A', between which the pitman B is vibrated to reciprocate the ram C longitudinally.

The cross-head D is shown upon the front 50 of the frame, as usual, for carrying the work-table and having a feed-screw F with gears f' and a rocker-lever g upon the end of the cross-head for turning such feed-screw.

A bearing G is formed upon the plate A of the frame, and two crank-gears H H' are 55 shown mounted by a journal I in such bearing, the gear H carrying the crank-pin J, which is fitted in the usual manner to a slot in the pitman B to vibrate the same as the crank-gears are rotated.

The gear H' next the plate is smaller than the gear H, and a stud K is supported by the frame adjacent to such gears, carrying two pinions L L', adapted to mesh, respectively, with the crank-gears H H' and journaled 60 upon the stud to move transversely when required, so that either of the pinions may be engaged with one of said gears, the pinions being so connected by a sleeve that the pinion L clears the rim of the gear H when the pinion L' is meshed with the gear H'.

To shift the pinions and set them in their two working positions, a sliding rod l' is extended through the frame and provided with jaws l' to embrace the rim of the larger pinion L', and the outer end of such rod is connected with a lever V, which is pivoted upon the outside of the frame-plate A. The handle of such lever may be moved to and from the plate and shifts the rod and pinions when 70 thus moved, and although they are not shown upon the drawings the rod is provided in practice with stops to locate each pinion as required in line with the corresponding crank-gear H H'.

The pinions when in operation rotate at the same speed, and thus rotate the crank-pin at different speeds.

The gear H' lies close to the plate A of the frame, and in order to retract the pinion L' 85 endwise from the gear H' a recess L' is formed in the plate adjacent to such pinion. The recess is also made to receive a double-face gear-wheel M, which is located partly in said recess and meshed with the pinion L' 95 and has a face of suitable breadth to engage the same in both positions of the said pinion.

A driving-shaft N carries the driving gear-wheel M and is extended outside of the frame-plate A and provided with a clutch gear-wheel O, which is connected with the shaft N at pleasure by a clutch P. It has preferably a hand-wheel S², which is omitted from Fig. 1 to show the clutch-sleeve and its fork P'. The clutch gear-wheel O is inclosed for protection in a guard-case O', and a clutch-lever

Q is pivoted upon such guard-case by a journal Q' and is extended forward by the side of the crank-planer frame toward the cross-head or work-table, so as to be conveniently reached by the operator when watching the work of the tool. The clutch-lever carries a fork P' to shift the clutch P.

An electric motor R is attached to the rear of the crank-planer frame and has its spindle S provided with a pinion S', which rotates within the guard-case O' and meshes with the clutch gear-wheel O.

As already described, the frame is of box form with flat sides A and A', and the rear end of the frame is also made flat and the electric motor attached to such flat surface between the lines of the two sides, so as not to project beyond the lines of their surfaces. The motor-spindle S and the driving-shaft N are both projected beyond the line of the frame A to receive the gear-wheels S' and O, and these gears thus lie close to the frame-plate A, so that the guard-case O' is readily attached thereto.

By attaching the electric motor in or at the rear of the shaper-frame it does not obstruct access to the side of the frame where the feed mechanism is located and where the operator stands to vary the adjustment of the pitman crank and the connection of the pitman with the ram. Such location is also an advantageous one, because the driving-shaft for the crank-gear is commonly in shapers located close to the rear part of the frame and is thus readily connected with the spindle of the electric motor by a reduction-gear O and S'. The location of the clutch upon the driving-shaft places it at a considerable distance from the operator, who usually stands at the right-hand side of the work-table in front of the cross-head; but the convenient operation of the clutch-lever by the workman is secured by projecting the clutch-lever forwardly within reach of the operator.

The electric motor is in practice furnished with the usual means to stop and start the same; but when the crank-planer is required for use the motor is usually rotated continuously and the clutch employed to stop and start the ram at frequent intervals, as may be required for the operation of the tool. Such stopping and starting of the tool is instantly effected by the connecting and disconnecting of the clutch-gear O with the driving-shaft N, and it is found in practice that this mechanism permits the stopping of the tool much more quickly than where the driving-shaft is provided with a speed-cone and heavy belt connected to the same, which when set in motion acquires so much momentum that it does not stop for some time after the motive power is disconnected.

With the construction shown there are no parts attached permanently to the driving-shaft which have any considerable momen-

tum, and the driving-shaft thus stops as soon as the clutch is disconnected therefrom.

The mechanism for operating the feed-arm consists of an eccentric ring or segment k, fitted to an eccentric groove k' in the outer face of the crank-gear H' and connected by a link l with a crank upon the inner end of the feed-shaft.

The feed-shaft a is shown journaled in the usual manner in a bearing b upon the frame-plate A, below the bearing G, and provided at its outer end with the feed-arm c and at its inner end with the crank d, to which the link l is pivoted.

The eccentric groove and segment give a uniform throw to the link l and a uniform degree of oscillation to the feed-arm c. In such feed-arm a dovetail or undercut groove is usually provided in which the inner end of an adjustable crank-pin m is secured and the outer end of such crank-pin pivoted to the connecting-rod h, which actuates the rocker g. The rocker g has a spring-pawl to engage the feed-gear f' in the usual manner. The feed crank-pin m is adjustable upon the feed-arm to vary the degree of feed, and being "overhung" it is sometimes so severely strained by the resistance of the feed-screw F that the crank-pin is broken at its neck. To strengthen the crank-pin, means are provided in the present invention to support its outer end efficiently while maintaining its adjustability to and from the center of the feed-shaft. Such support is secured by forming the outer end of the crank-pin m with a nut n and mounting the adjusting-screw j in the same and in bearings i, projected outwardly from the ends of the feed-arm c.

When the feed crank-pin is adjusted by turning the screw, the outer end of the pin is firmly supported thereby, while the inner end is supported by the groove or longitudinal slot in the feed-arm c, to which it is snugly fitted. The feed crank-pin is thus supported at its inner and outer ends and is thus protected from bending or rupture under any normal strain.

The improvements in the crank-gear increase its range of speed very materially, the improvements in the feed-arm increase the durability of the feed crank-pin, and the improvements in the driving-shaft connections enable the electric motor to be used advantageously and the movements of the ram controlled with the utmost precision by means of a clutch-lever in reach of the operator while in his working position. The use of such a clutch furnishes a means of disconnecting the machine from its motive power much more quickly than can be done by the shifting of a belt upon speed-pulleys, and the stopping of the machine when the driving-shaft is unclutched is greatly facilitated by the use of a brake at such time.

With the construction shown the opera-

tion of the clutch-lever serves when the clutch-hub is retracted to actuate a brake by pressing the clutch-hub P against the hub of the hand-wheel S² upon the driving-shaft N. The hub of the hand-wheel is shown in Figs. 3 and 4 faced with leather, and the clutch-hub is embraced by the fork P', connected with the hand-lever Q, as shown in Figs. 1, 3, and 4. When the clutch-hub is pressed hard against the hand-wheel, the friction of the fork upon the clutch-hub develops sufficient resistance (with the train of gearing shown in Fig. 5) to stop the crank-gear and the ram almost instantly. Such arrest of the crank-gear results because the clutch detaches the driving-shaft entirely from the gearing which connects it with the motor, and the momentum of the motor and its connected gears have thereafter no effect upon the driving-shaft. This is a matter of great convenience in setting the ram quickly in various positions with the aid of the gearing to determine the stroke of the tool and its relation to the work-piece.

25 We are aware that it is not new to connect an electric motor with a machine-tool for driving the same and that it is not new to connect a clutch and brake to operate as described, and what we have claimed in the 30 present application is therefore the particular construction and arrangement of these parts.

Having thus set forth the nature of the invention, what is claimed herein is—

1. In a metal-shaper having a frame with 35 ram C in the top and a pitman B vibrated to reciprocate the same, the combination, with the frame, having the bearing G at one side of the pitman, of the crank-gear shaft I journaled therein, the crank-gears H and H' of 40 diverse sizes secured together upon such shaft within the frame and the gear H next the pitman B having the crank-pin J to engage the pitman, the driving-shaft N having the double-face gear-wheel M, the intermediate shaft K with the pair of pinions L and L' of diverse sizes connected by a sleeve and mounted to move longitudinally thereon, and adapted to mesh respectively with the crank-gears H and H' and to clear the larger gear H 45 when required, the sliding rod l² extended through the frame at the edge of the pinion L' and provided at its inner end with the jaws l' to embrace the rim of said pinion, and at its outer end with the lever V, the frame 50 having the recess L² to receive the pinion L' when retracted from the gear H' and the driving gear-wheel M located partly in said recess, and the larger pinion L' meshing at all 55 times with the gear-wheel M and operating merely as an intermediate without affecting the speed when meshed with the wheel H', and the two pinions L, L' operating as a re-

duction-gear when the pinion L is meshed with the larger wheel H, the whole arranged and operated substantially as herein set forth. 65

2. The metal-shaper having a rectangular box-frame, the ram C upon the top of the frame, and a vibrating pitman to propel the same, with a crank-gear inside the frame to vibrate the pitman, the driving-shaft N extended across the frame with gearing connected to such crank-gear, the motor R attached to the rear side of the box-frame and having its spindle projected beyond one side of the frame and provided with the pinion S', the 70 gear-wheel O upon the driving-shaft at the same side of the frame meshing with the pinion S', the clutch for connecting the gear-wheel O with the shaft N at pleasure, the guard-case O' sustained upon the frame and inclosing the motor-pinion and the gear-wheel O, 75 bearings upon the guard-case, and a journal Q' fitted to the said bearings and provided with the clutch-fork P' and with the clutch-lever Q projected toward the cross-head of 80 the machine, the whole arranged and operated substantially as herein set forth.

3. In a metal-planing machine, driving mechanism therefor, consisting of a high-speed driving-shaft, a double-faced pinion secured 90 to said shaft, an intermediate shaft, having slidingly mounted thereon a pair of intermediate gears of diverse size, rigidly connected together, the larger of said gears meshing at all times with said double-faced pinion, a 95 third shaft having secured thereto a pair of gears of diverse size, means whereby said intermediate gears may be alternately shifted respectively into engagement with the gears on said third shaft, and means for connecting said last-mentioned gears with driven parts of the planing-machine. 100

4. A metal-planing machine having in combination, a reciprocating tool-carrying ram, a driving-pitman connected to said ram, means 105 for driving said pitman comprising a driving-shaft having secured thereto a double-faced gear, an intermediate sliding gear of larger diameter meshing at all times with said double-faced gear, a gear of smaller diameter 110 spaced from but secured to said intermediate gear to slide and rotate with the same, and two large gears of diverse size connected to rotate together and designed to engage alternately the intermediate gears, and means connecting said large gears with said pitman. 115

In testimony whereof we have hereunto set our hands in the presence of two subscribing witnesses.
